UNITED STATES PATENT OFFICE.

WILLIAM H. MCKISSICK, OF TULSA, OKLAHOMA.

MEANS FOR DRAINING WELL TUBING PREPARATORY TO PULLING SAME.

Application filed March 29, 1924. Serial No. 702,777.

To all whom it may concern:

Be it known that I, WILLIAM H. MCKISSICK, a citizen of the United States, residing at Tulsa, in the county of Tulsa and State of Oklahoma, have invented a certain new and useful Improvement in Means for Draining Well Tubing Preparatory to Pulling Same, of which the following is a full, clear, and exact description, reference being had to the accompanying drawings.

This invention relates to means for draining the tubing of deep wells, such as oil wells, prior to pulling the tubing.

As to the generic matter, the present application is a division of my former application Serial No. 571,502, filed June 28, 1922.

In the working of oil and other deep wells it becomes necessary at comparatively short intervals to pull the tubing for the purpose of repairs, as for the replacement of the pump cups or pump valves, or the renewal of the standing valve. In the normal operation of the pump, the standing valve opens as the pump piston ascends, letting into the working barrel and tubing a quantity of liquid according to the lift of the piston, and closes when the piston ceases to ascend and remains closed during its descending stroke, the piston incorporating an upwardly opening valve through which the liquid passes as the piston descends. When it is desired to inspect or repair the parts above referred to, the string of sucker rods (which carries at its lower end the pump piston) is first withdrawn from the tubing and the tubing is then pulled. Now, unless the liquid within the tubing is drained back into the well, it results in the loss of this liquid and in the saturation of the equipment, such as the bull ropes and belting. Furthermore, and very obviously, it takes considerably longer to pull "wet" tubing than tubing from which the liquid has been drained.

It is the fundamental purpose of my invention to provide a comparatively simple, efficient and particularly convenient means, for draining the liquid from the tubing prior to withdrawing it from the casing, eliminating the difficulties above set forth and saving the liquid which is otherwise lost and avoiding the great inconvenience, annoyance and waste of time incident to the pulling of "wet" tubing.

In the accompanying drawings, Fig. 1 is a longitudinal section through well tub-

ing equipped with one form of my invention, showing the valve closed; Fig. 2 is a similar view showing the valve opened by a weight that has been dropped into the tubing; Fig. 3 is a transverse section on the line 3—3 of Fig. 2; Fig. 4 is a view similar to Fig. 2 of another form of the invention; while Figs. 5 and 6 are fragmentary longitudinal sections through well tubing equipped in the respective views with the two forms of the invention above referred to and showing the valves unseated by the pump piston in accordance with the method above described.

In the form of the invention illustrated in Figs. 1, 2, 3 and 5, I interpose a body portion 1 between sections 2 and 3 of the well tubing. This body portion has a through passageway 5 which, throughout the greater portion of its length, is of substantially the same diameter as the inside dimension of the tubing. At its ends, the passageway is enlarged and threaded for the reception of the externally threaded ends of the tubing sections. The threading of the tubing sections is in accordance with standard practice, the sections ordinarily being connected together by suitable couplings. The body portion 1 has a lateral extension 6 enclosing a valve chamber 7 which opens into the passageway 5 through a port 8. Screwed up through a tapped hole in the bottom wall of the chamber 7 is a nipple 9, the inner end of which constitutes a seat for a ball valve 10. This ball valve and a valve actuating ball 11 are adapted to be placed in the chamber 7 through the opening into which the nipple 9 is screwed prior to the insertion of the ball. It will be observed that the vertical dimension of the port 8 is less than the diameter of the balls 10 and 11 so that there is no danger of the balls becoming lost through said port. It will also be noted that the aggregate diameter of the two balls is substantially equal to the distance between the opening of the port 8 and the opposed wall of the chamber 7. An abutment 12 is formed within the passageway 5 slightly below and diametrically opposite the port 8.

When it becomes necessary to pull the tubing for reasons already related, the string of sucker rods, designated 15, with the pump piston attached to its lower end, is withdrawn from the tubing, leaving in the tub-

ing the column of liquid that has been elevated by the pump. The tubing is then raised until the valve above described reaches approximately the fluid level within the well in a manner which will be readily understood by those familiar with deep well operations, and a tubular weight 16 (Figs. 2 and 3) is then dropped into the tubing. The weight descends therein (the liquid 10 passing through the bore of the weight during the descent) until it reaches the abutment 12, the tapered upper surface of said abutment thrusting the weight laterally against the actuator ball 11, displacing said ball inwardly and causing it to remove the ball valve 10 from its seat which allows the liquid to flow back into the well. The empty tubing may then be readily pulled.

The foregoing operation is in accordance 20 with the method disclosed and claimed in my earlier application above identified.

In the form of the invention illustrated in Fig. 4, separate sections of the tubing are designated 20 and 21 and to the lower end 25 of the former section is screwed the body portion or casing member 22 of the drain valve within an offset 23 whereof is pivoted, upon a pin 24, a trigger or lever 25 which is adapted to engage and remove from its seat a ball valve 26, the trigger or lever being normally held away from the ball by means of its weighted end 27, the normal 30 position of the trigger or lever being indicated in dotted lines. A seat for the ball valve 26 is shown as provided by the inner end of a nipple 28 that is threaded upwardly through a tap hole in the lower side of the offset 23.

Screwed into the lower end of the casing 40 22, in axial alignment with the tubing section 20, is a nipple 30. The internal diameter of this nipple is somewhat less than that of the tubing, it being found that a nipple which is $1\frac{3}{4}$ inches inside diameter 45 is suitable for use with the standard 2 inch internal diameter tubing. The upper end of the nipple, therefore, constitutes an abutment or shoulder 31 that is a slight distance below the plane of the lever 25. The nipple 50 30 has connection, through a coupling 33, with the lower tubing section 21, and, as will be readily understood, the working barrel of the pump is applied to the tubing at a suitable distance below this point.

Using this form of the invention in accordance with the method disclosed in my earlier application, after the string of sucker rods and pump piston have been withdrawn, the tubing is elevated until the valve 60 is at about the fluid level within the well, when a tubular weight 35 is dropped into the tubing, the weight descending therein until it engages the shoulder 31. When in this position, the weight 35 retains the lever 65 25 in the full line position of Fig. 4, where-

in it engages the ball 26 to hold it off its seat, allowing the liquid within the tubing to drain back into the well. The weight 35 is of a diameter between the internal diameters of the nipple and tubing so that it 70 will be sustained by the shoulder 31 and leave ample room between it and the wall of the tubing to permit the liquid to flow freely past it.

The manner of practicing the method 75 which constitutes one phase of my present invention is illustrated in Figs. 5 and 6. In Fig. 5 the string or sucker rods 15 has been raised until the pump piston 36 which is attached to its lower end is brought into 80 engagement with the actuator ball 11, thrusting the ball inwardly until it removes the ball valve 10 from the valve seat, allowing the liquid above the piston to flow back into the well.

In Fig. 6, the pump piston is shown as displacing the lever 25 which results in the lever lifting the ball valve 26 from its seat 90 so that the liquid may be discharged from the tubing into the well.

It will be seen that the last described method has the advantage of emptying the tubing above the drain valve prior to the withdrawal of the sucker rods and piston, rendering the operation cleaner and more convenient.

The importance of the invention, especially as used in connection with oil wells, will be more fully appreciated when it is pointed out that a barrel of oil weighs 297 pounds; that there are approximately four barrels of oil to 1000 feet of 2 inch tubing and approximately nine barrels of oil to 1000 feet of 3 inch tubing, and that oil wells of from 3000 to 4000 feet deep are not uncommon. From this it will be seen how much more work is imposed upon the rigging in pulling "wet" tubing than in pulling tubing from which the oil has been drained. One is also reminded of the great loss of oil incident to pulling "wet" tubing. Also, much time is saved by draining the tubing before pulling it as naturally the work is greatly hampered by the presence of the oil.

I would also call attention to the fact that my invention is applicable to standard practice, it being only necessary to insert the drain valve when assembling and lowering the tubing, and it should not be confused with draining means for pumps made necessary by special equipment involving tubular pump rods, liquid sealed pump pistons, etc., and wherein no provision is made for draining the tubing proper preparatory to pulling it.

Having thus described my invention, what I claim is:—

1. A drain device for well tubing comprising a body portion having a through passageway and to which sections of a well tub-

- ing are adapted to be applied, the body portion having a branch port leading from the through passageway, a ball valve controlling the port, an actuator ball adapted to project through said port into the passageway, and a member adapted to be positioned within the passageway for engaging the actuator ball and through the intervention thereof remove the ball valve from its seat.
2. A drain device for well tubing comprising a body portion having a through passageway and which is adapted to be incorporated in said tubing with its through passageway in alignment with the bore of the tubing, the body portion having a lateral offset enclosing a valve chamber which communicates with the passageway through a port, the valve chamber having an outlet, a ball valve arranged to control the outlet, an actuator ball disposed within the chamber and arranged to project through the port into the passageway, and a member adapted to be positioned within the passageway and engage the actuator ball for shifting it laterally and through the intervention of said actuator ball remove the ball valve from its seat.
3. A drain device for well tubing comprising a body portion having a through passageway and which is adapted to be incorporated in said tubing with its through passageway in alignment with the bore of the tubing, the body portion having a lateral offset enclosing a valve chamber which communicates with the passageway through a port, the valve chamber having an outlet, a valve arranged to control the outlet, an actuator disposed within the chamber and arranged to project through the port into the passageway, and a member adapted to be positioned within the passageway for engaging the actuator thereby to shift it laterally and through the intervention of said actuator remove the valve from its seat.
4. A drain device for well tubing comprising a body portion having a through passageway and which is adapted to be incorporated in said tubing with its through passageway in alignment with the bore of the tubing, the body portion having a branch port leading from the through passageway, there being an abutment within said passageway, a ball valve controlling the flow of liquid through the branch port, an actuator ball arranged to project through the port into the passageway, and a member adapted to be positioned within the passageway against the abutment for engaging and shifting laterally the actuator ball and through the intervention thereof actuate the ball valve.
5. A drain device for well tubing comprising a body portion having a through passageway and which is adapted to be incorporated in said tubing with its through passageway in alignment with the bore of the tubing, the body portion having a lateral offset enclosing a valve chamber which communicates with the through passageway through a restricted port, the bottom wall of the valve chamber having an opening, an actuator ball and a ball valve that are adapted to be placed into the valve chamber through said opening, a tubular member engaged within said opening and having its inner end formed to provide a seat for the ball valve, the actuator ball being adapted to project through the restricted port into the through passageway, and a member adapted to be positioned within said passageway for engagement with the actuator ball thereby to shift it laterally and through the intervention of said actuator ball remove the ball valve from its seat.
6. A drain device for well tubing comprising a body portion having a through passageway and to which sections of a well tubing are adapted to be applied, the body portion having a branch port leading from the through passageway, a ball valve controlling the port, an actuator adapted to project through said port into the passageway, and a member adapted to be positioned within the passageway for engaging the actuator and through the intervention thereof remove the ball valve from its seat.
7. A drain valve for well tubing comprising a body portion having a through passageway and to which sections of a well tubing are adapted to be applied, the body portion having a branch port leading from the through passageway, a valve controlling the port, an actuator independent of, and movably supported by the body portion in operative relation to, the valve and adapted to project through said port into the passageway, and a member adapted to be positioned within the passageway for engaging the actuator and through the intervention thereof remove the valve from its seat.

In testimony whereof, I hereunto affix my signature.

WILLIAM H. McKISSICK.
